UNITED STATES PATENT OFFICE.

JOHN KNOCHE, OF CINCINNATI, OHIO.

CLOTHES-SPRINKLER.

SPECIFICATION forming part of Letters Patent No. 254,222, dated February 28, 1882.

Application filed November 22, 1881. (No model.)

To all whom it may concern:

Be it known that I, JOHN KNOCHE, of Cincinnati, county of Hamilton, State of Ohio, have invented certain new and useful Improvements in Clothes-Sprinklers, of which the following is a specification.

The object of this invention is a cheap convenient device for sprinkling clothes. It consists in a convenient means for attaching a sprinkling-nozzle to an elastic bulb, and also in the peculiar arrangement of the outside collar.

In the accompanying drawings, forming part of this specification, Figure 1 is a central vertical section of my sprinkler and water-vessel. The sprinkler is shown charged ready for use. Fig. 2 is an enlarged axial section of the sprinkling-nozzle and collars by which it is secured to the rubber ball.

Referring to the parts, A represents a hollow rubber globe, (for my purpose the common rubber toy ball will answer,) having a small perforation through its shell.

B is a metal nozzle having a rose head or cup with fine perforations at its outer end. The opposite end is turned down, leaving a square shoulder, against which the flanged washer or collar C is seated. When the nozzle is secured to the ball A the lower or inner end of the nozzle is exteriorly threaded to receive the circular screw-threaded nut or washer D. The face of the collar C which bears against the rubber is made concave, and the face of the washer D convex, to conform to the shape of the globe A.

The nozzle is secured to the globe by first inserting the nut D through the perforation in the globe edgewise, and holding it in place (with the perforations in the globe and nut in

line) by compressing the globe between the fingers until the nut is firmly clasped. The nozzle B is then screwed into the nut D until the shell of the globe is compressed between the collars C and D. The nozzle B is of course made to turn freely in the collar C.

The covered cup E is made with a depression in the cover, so that any dripping when the sprinkler is withdrawn will run back into the vessel E. The collar C has a flange, e, which rests upon the vessel-cover around the central perforation when the nozzle is inserted. (See Fig. 1.) This flange is partially cut away to admit air to the vessel.

When my device is to be used the bulb is compressed, and so held while the nozzle is inserted through the perforation in the cover of cup E. It is then released and left in the position shown in Fig. 1. In a short time the pressure of air upon the surface of the water in the vessel will force the water into the bulb, which is then discharged in a fine shower upon the clothes through the perforated cup. When not in use the sprinkler is placed in the filling-vessel. Thus it will be kept constantly charged.

Instead of the flanged and cutaway collar C, upward spurs may be arranged around the perforation in the cover of vessel E, upon which a flat washer or collar upon nozzle B may rest.

What I claim as new, and desire to secure by Letters Patent, is—

The combination, substantially as specified, of bulb A, nozzle B, flanged collar C, and threaded nut D, for the purpose set forth.

JOHN KNOCHE.
